E. L. KRAM.
LOOSE LEAF BINDER.
APPLICATION FILED NOV. 14, 1918.

UNITED STATES PATENT OFFICE.

ERIK L. KRAG, OF CHICAGO, ILLINOIS.

LOOSE-LEAF BINDER.

1,320,479.

Specification of Letters Patent.

Patented Nov. 4, 1919.

Application filed November 14, 1918. Serial No. 262,513.

To all whom it may concern:

Be it known that I, ERIK L. KRAG, a citizen of the United States, residing at Chicago, in the county of Cook and State of Illinois, have invented certain new and useful Improvements in Loose-Leaf Binders, of which the following is a description, reference being had to the accompanying drawings, forming a part of this specification, in which corresponding numerals of reference in the different figures indicate like parts.

The object of my invention is to provide a simple, cheap and effective locking device for loose-leaf binders, which shall be so constructed as to insure its ready and easy operation regardless of rust or other similar causes which tend to affect metal surfaces when in continuous use under varying atmospheric conditions. To this end, my invention consists in the combination of elements hereinafter more particularly described and definitely pointed out in the claims.

25 In the drawings,

Figure 1, is an end view of a binder embodying the features of my invention,

Fig. 2, is a sectional view of a portion thereof, taken upon the line 2—2, Fig. 1, 30 viewed in the direction of the arrows there shown, and

Fig. 3, is a sectional view taken upon the line 3—3, Fig. 2, viewed as indicated by the arrows.

35 Referring to the drawings, 1 indicates cover supports of any approved form to which lids 2, are hinged by means of flexible covering material. Said supports are rigidly attached in any approved way to 40 counterpart binding members generally designated by 3 and 4. Said binding members are formed from sheet metal and consist of parts 5 and 6, extending throughout the length of the binder and hinged to each 45 other at 7. Integral with said members 5 and 6 and bent in opposite directions at substantially right angles thereto, are portions or members 8 and 9 having flanges 10 and 11 respectively, formed thereon, which flanges 50 are intended to be substantially parallel to each other when the binder is closed,—the cover-supports 1, 1 being rigidly attached thereto, as are also plates 12 and 13, which serve as supports for the usual binder 55 prongs 14.

A locking-bar 15, of a length preferably

corresponding substantially to that of the binding members, is located outside of and parallel to the member 9 and adjacent to the member 6. Said bar is formed from sheet-metal and is concavo-convex in cross-section. This construction not only imparts rigidity to the bar but provides what may be termed longitudinal knife-edge bearings 16, 17, Fig. 3, against the outer face of the part 9. 60 Clips, generally designated by 18, are attached to the plate 9 by means of rivets 19 and serve to hold the bar 15 in place while permitting it to slide longitudinally. It will be noted that said clips are so formed as that 70 each will contact with the bar at two portions only, viz: the outer edge of the bar and upon a longitudinal line upon the outer convex face thereof, as shown at 20. From the description given, it will be apparent 75 that an accumulation of rust upon the bar as would be likely to occur in ordinary use, would not be sufficient to prevent its free longitudinal movement.

A series of registering slots 21, 22, Fig. 2, 80 is formed in the members 5 and 6, for the reception of laterally extended detents 23, formed upon the locking-bar 15. A coiled spring 24 has one end attached to the part 6 and the other to the bar 15, thus enabling 85 it to yieldingly hold said bar in a locked position. A thumb-piece 25, formed upon the outer end of the bar, enables the latter to be pushed inwardly for the purpose of unlocking it. 90

Practice has demonstrated that the locking member described will not become rust-bound under the most humid atmospheric conditions.

Having thus described my invention, I 95 claim:

1. The combination with the binding members of a loose-leaf binder, of a longitudinally arranged, spring-controlled locking bar slidably mounted upon one of said members, said locking bar being concavo-convex in cross section with its edges only in contact with said member, and having detents for engaging the counterpart of the member to which it is attached, and guiding 100 means for holding said member in its path of movement.

2. The combination with the binding members of a loose-leaf binder of a longitudinally arranged slidable locking-bar 110 mounted upon one of said members, said bar being concavo-convex in cross section with

- knife-edges formed on the concave side thereof and lying in contact with the face of said member, laterally extended detents formed upon said locking-bar and arranged 5 to pass through slots for engaging the counterpart of the member to which said bar is attached, guiding means for engaging the convex surface of said locking-bar and means for normally holding said bar in a 10 locked position.
3. The combination with the hinged binding-members of a loose-leaf binder, of a longitudinally-disposed slideable locking-bar mounted upon one of said members, said bar 15 being concavo-convex in cross section with its concave side facing the member to which

it is secured, guide members therefor, laterally extended detents formed upon said locking-bar and arranged to pass through slots formed in said binding member and its counterpart for locking said members together and a spring for normally holding said bar in a locking position. 20

In testimony whereof I have signed this specification in the presence of two subscribing witnesses, this twelfth day of November, 1918. 25

ERIK L. KRAG.
